ARCH SUPPORTER

Vincent R. Casey and George A. Larsen, Portland, Oreg., assignors to C & L Method of Foot Correction, Portland, Oreg., a corporation of Oregon

Application June 5, 1935, Serial No. 25,147

2 Claims. (Cl. 36—71)

The present invention relates to the art of orthopedics and it particularly has reference to appliances for the correction of the arches of the foot, both the metatarsal arch and the main or longitudinal arch.

The invention has for its objects to provide an appliance which is sufficiently resilient and flexible to permit the foot of the user to flex and move, thus exercising and building up the weakened muscles; to provide an appliance which, due to its peculiar construction and method of manufacture, is impervious to either hot or cold water and, therefore, may be used in any sort of foot covering, wading boots, or other foot coverings which are subject to moisture, either from the perspiration of the foot or from outside sources; to provide an appliance which fits perfectly and keeps the foot during actual use of the appliance in proper condition and the bones of the foot in proper alignment.

The best way to constitute the supporter is by the following steps taken in the order mentioned:

First:—A wax impression of the foot is taken. Ordinary dental wax is slightly heated so as to make the same pliable and after the bones of the foot are placed in proper alignment the wax is applied to the foot, thus obtaining an exact reproduction of the foot as it should be normally and as it should be to give comfort and proper use to the patient.

Second:—A plaster of Paris cast is taken from the wax impression. Ordinary plaster of Paris of proper consistency is poured over the wax impression of the foot giving an exact cast upon which the appliance can be molded.

Third:—The cast is covered with gauze. After the plaster of Paris is thoroughly set there is placed about the same a piece of light gauze to be used for the first covering.

Fourth:—The gauze covering of the cast is treated with a glue-like substance. After the plaster of Paris cast has been covered with the gauze, the same is coated with a glue-like binding substance (which will hereinafter be more specifically defined) so that the gauze becomes firmly and evenly attached to the plaster of Paris cast. Two coatings preferably of this "glue" are applied some four or five hours apart and the cast is allowed to harden for a period of 24 hours after the last application of the "glue".

Fifth:—A piece of pig skin is shaped to conform approximately to the contour of the foot impression and roughened to more readily absorb the "glue" into its pores. This pig skin is

then coated on one side with the "glue" and is cemented thereby to the top of the gauze covered cast and permitted to stay there for approximately 2 hours. After the cemented pig skin has been permitted to harden for a period of approximately 1 hour there are prepared small pieces of leather to correspond to the metatarsal impression in the cast and these pieces of leather which, depending upon the depth of the metatarsal impression, may consist of several pieces, are placed over the metatarsal impression in the pig skin covered cast and by means of a suitable clamp are forced firmly and evenly down into the metatarsal impression and are held firmly in place by the clamp. The clamp is permitted to remain in position for a period of at least 24 hours. The result of this operation is to force the pig skin covering into the metatarsal impression, being thus in position and permitted to stand for a period of 24 hours the "glue" covering will have thereupon firmly cemented the pig skin into the metatarsal impression. The clamp and the several small pieces of leather above referred to are thereupon removed.

Sixth:—The exposed face of the pig skin is then coated with two or three coverings of "glue", permitting each to harden for a period of approximately 8 hours.

Seventh:—The cast is then wrapped in a cover of canvas (preferably ten ounce canvas), the canvas having been previously thoroughly coated on the inner side with glue. The canvas is carefully pressed down and molded over the cast so that it will be smooth and properly adhere at each point. It is then permitted to set for a period of at least 24 hours until the glue hardens and the canvas is firmly fixed upon the cast.

Eighth:—The canvas is then treated with "glue". There are applied three additional coatings of "glue" over the canvas, each being permitted to set between applications approximately 8 hours.

Ninth:—Another layer of pig skin is then cemented to the canvas. This pig skin is shaped to the approximate outline of the foot impression and prepared as in the fifth step above mentioned and applied over the canvas in the same manner as the piece in the fifth step was applied.

Tenth:—After removal of the clamp, etc. the pig skin is properly skived and treated with two or three coats of "glue" with 8 hour intervals between them for hardening.

Eleventh:—A second envelope of canvas is now prepared and placed around the cast in the same

manner as that in the seventh step above mentioned.

Twelfth:—After the second canvas envelope has been cemented down firmly and smoothed over the pig skin and the cement has duly hardened, the last canvas is covered with a coating of the "glue" into which has been stirred or mixed aluminum dust so as to give a finish to the appliance. This gives the appearance of 10 silver plating. Different colors may be obtained by the use of different colored dust or pigment.

Thirteenth:—After the mass resulting on completion of the twelfth step has been allowed to set for a period of 24 hours a final coat of clear 15 "glue" is put over the top of the aluminum colored glue and permitted to set for 24 hours. The appliance is then complete on the cast.

Fourteenth:—The cast is then removed from the appliance by cutting through the canvas covering and "glue" on the sides at a place where the plaster cast meets the appliance, i. e., along the outline or marginal edge of the appliance.

Fifteenth:—After the plaster of Paris cast has been removed the appliance is ready to have 25 placed thereupon a leather covering. This covering is prepared from a piece of soft calf skin properly cut to be placed on the appliance face which was against the plaster of Paris cast. Before the leather covering is placed upon the appliance the top edges of the appliance are skived and buffed so as to remove any possible irregularities and also that the covering will firmly adhere thereto. After this is done the top calf skin covering is pasted upon the face of the appliance 30 opposite to that having the aluminum coloring by means of rubber cement and the appliance is then complete.

In the accompanying drawing to which reference is made as a part of this specification—

40 Figure 1 is a plan view of the finished appliance looking at the same from the underside.

Figure 2 is a plan view of the finished appliance looking at the same from the upper side.

45 Figure 3 is a detail cross section on a magnified scale taken on the line 3—3 of Figure 2.

In the accompanying drawing, in which like numerals of reference indicate like parts in all of the figures, 3 represents the gauze layer, 4 and 5 the pigskin layers; 5 and 7 the canvas layers, 50 8 the calfskin top layer on which the wearer's foot rests. While I have referred to and prefer to use pig skin, other kinds of leather which may be found the equivalent of pig skin may be used in lieu thereof.

55 The glue-like substance herein referred to as "glue" is a substance known under the name "Kayon" and is manufactured by the Kayon

Manufacturing Company of Milwaukee, Wisconsin. There also may be used a glue known as Carlson's "Elyster", manufactured by the Carlson Company of Illinois. While we prefer to use "glues" of the kind just referred to, it is 5 obvious that other suitable adhesives may be found satisfactory and can therefore be employed in lieu of the specific "glues" above mentioned.

The appliance constructed in accordance with the foregoing method has the following characteristics, viz: 10

First:—It is very strong and at the same time pliable;

Second:—The resiliency and flexibility of the appliance permits the foot of the user to flex 15 and move, thus exercising and building up the weakened muscles, a thing that a rigid appliance would not permit;

Third:—Due to its construction the appliance is impervious to either heat or cold and therefore 20 may be used in any sort of foot covering, wading boots or other foot covering subject to moisture, either from the perspiration of the foot or from outside sources;

Fourth:—The appliance being built upon a 25 mold or cast of plaster of Paris manifestly fits perfectly and keeps the foot during actual use of the appliance in proper condition with the bones in alignment.

From the foregoing description, taken in connection with the accompanying drawing, it is 30 thought the complete construction, operation and advantages of the invention will be readily apparent to those skilled in the art.

What we claim is:

1. In an arch supporting appliance, a body 35 composed of successive layers of gauze, pig skin, canvas, pig skin and canvas, secured together with glue, a calf skin layer glued over the exposed face of the first gauze layer, and a coating of glue mixed with a coloring matter over the exposed face of the canvas layer.

2. In an arch supporter, a body composed of the following parts in successive layers as an integral structure, viz: a layer of gauze, a layer 45 of pig skin, a layer of canvas, another layer of pig skin, and another layer of canvas, the several layers being arranged in the order mentioned, the last canvas layer constituting the bottom of the supporter and a soft leather surface layer glued over the gauze layer and itself constituting the 50 top of the supporter, the body being of a shape to conform to the foot of the wearer, and the successive layers being glued together.

VINCENT R. CASEY.
